(57) **CLAIM**

The ornamental design for an earth wall as shown and described.

DESCRIPTION

FIG. 1 is a top perspective view of an earth wall according to our new design;

FIG. 2 is a front view thereof;

FIG. 3 is a rear view thereof, shown such that portions of the earth wall are visible;

FIG. 4 is a side view thereof, shown such that portions of the earth wall are visible;

FIG. 5 is another side view thereof, taken opposite the view of FIG. 4, and shown such that portions of the earth wall are visible;

FIG. 6 is a top view thereof; and,

FIG. 7 is a bottom view thereof, shown such that portions of the earth wall are visible.

The broken lines form no part of the claimed design.
